UNITED STATES PATENT OFFICE.

JOHN BUNN, OF BINGHAMTON, NEW YORK, ASSIGNOR OF ONE-HALF TO
C. J. LEWIS, OF SAME PLACE.

CIGAR-ROLLING MACHINE.

SPECIFICATION forming part of Letters Patent No. 566,058, dated August 18, 1896.

Application filed January 8, 1896. Serial No. 574,711. (No model.)

To all whom it may concern:

Be it known that I, JOHN BUNN, a citizen of the United States, residing at Binghamton, in the county of Broome and State of New York, have invented certain new and useful Improvements in Cigar-Rolling Machines; and I do hereby declare the following to be a full, clear, and exact description of the invention, such as will enable others skilled in the art to which it appertains to make and use the same, reference being had to the accompanying drawings, which form part of this specification.

My invention relates to cigar-rolling machines designed to apply the wrapper to the cigar-bunch, and has for its object to increase the effectiveness of machines of this class, whereby better results may be attained.

The principal features of my invention are a series of adjustable pressure-rollers arranged end to end, which bear on the cigar-bunch while it is being rolled, each roller being separately adjustable, whereby the pressure can be applied uniformly over the length of the bunch irrespective of its shape, and a pivoted table on which the wrapper is supported while being wound on the bunch. These and other features of my invention will be hereinafter fully described, and more particularly pointed out in the claims.

Referring to the drawings, Figure 1 represents a top view of my improved machine. Fig. 2 is a front view showing the rollers in a tilted position. Fig. 3 is a rear view showing the rollers in the same position as in Fig. 2. Fig. 4 is a vertical sectional view on the line $\alpha\alpha$ of Fig. 1. Fig. 5 is a view of the stretcher detached from the machine. Fig. 6 is a sectional detail view of part of one of the posts and gearing. Fig. 7 is a view of the presser-rollers detached and showing a modification, and Fig. 8 is a sectional view of a detached detail. Fig. 9 is a sectional view of a portion of the wrapper-supporting table and a plate on which it is adjustably supported. Fig. 10 is a plan of a portion of the bed-plate of the machine, showing a detail of construction.

Similar letters of reference indicate corre-

sponding parts in each figure of the drawings.

A represents the bed-plate of the machine, from which the standards a , a' , and a^2 rise.

B is the main driving-shaft, journaled in the standards a and a' , and provided with suitable driving-pulleys b . The shaft B carries a gear b' , which is intermediate of and meshes with similar gears c' and d' on the ends of the shafts c and d , journaled in the standards a' and a^2 , and which carry the rollers C and D, which rollers are therefore positively driven. The rollers C and D support and rotate the bunch while it is being wrapped.

E is a hollow standard enlarged at its lower end, and adjustably held in the elongated opening e in the bed-plate A by means of the clamping-nut e' , as shown in Figs. 3, 8, and 10. The upper end of the standard is split and provided with the exterior clamping-nut e^2 .

F is a post adapted to fit in the hollow standard E, and is adjustably held therein by the clamping-nut e^2 , as shown in Fig. 8. The post F is provided at its upper end with a plate f , having downwardly-extending ears f' .

G is another plate provided with downwardly-extending ears g , which are hinged to the ears f' by means of the rod g' . A coiled spring g^2 is arranged on the rod g' and is so connected to the plates f and G as to normally force the plate G against the plate f , the latter being stationary and the former movable on the hinged joint. A lever g^3 extends rearwardly from the plate G from, which a rod g^4 extends to a foot-treadle (not shown) beneath the bed-plate, which enables the operator to lift the plate G against the force of the spring g^2 , as will be referred to herein-after.

The plate G is provided with suitable boxes h , in which the rods h' , h^2 are journaled. These rods are adapted to have rotary and longitudinal movement in the boxes h , h^2 , and are held in the desired position by set-screws h^3 , h^4 . To the front ends of the rods h' , h^2 are hinged the shanks h^5 of the frames h^4 , carrying the presser-rollers H, the latter being

arranged end to end. The rollers H can therefore have a swinging vertical adjustment relative to the rods $h' h'$, and be held in any desired position by the screws $h^5 h^5$, which form the pintles of the hinges.

As the standard E can be adjusted on the bed-plate A, it follows that the post F and all it carries are also adjustable relative to the bed-plate, and such adjustment results in 10 adjusting the presser-rollers H longitudinally relative to the rollers C and D.

I is a set-screw working in the plate G and engaging the plate f, and by means of which the plate G and the presser-rollers H are vertically adjusted and the downward pressure 15 of the said rollers on the tobacco bunch, caused by the action of the spring g^2 , is restricted and regulated.

From the foregoing it will be seen that the 20 presser-rollers H H have a spring-actuated pressure on the tobacco bunch when the latter is supported on the rollers C D, which pressure can be adjusted, and also that said rollers can be separately adjusted relatively 25 to the rollers C D, so that they will lie in planes either parallel with the planes of the rollers C D or at any desired angle thereto, and also that they can be adjusted vertically, laterally, and longitudinally to the rollers C 30 D, so that various sized and shaped bunches may be operated on in such manner that substantially uniform pressure is applied throughout the length of the bunch; also that by operating the foot-treadle connected 35 with the rod g^4 the presser-rollers H H can be elevated simultaneously to enable the operator to insert a bunch or remove a cigar from the supporting and rotating rollers C and D.

40 J is the stretcher attached to and supported by the standard a^2 to have a slight vertical and lateral adjustment relative to the rollers C and D. This stretcher is a metal plate convex in cross-section and tapering slightly 45 from the butt to the tip end, as shown in Fig. 5. It is provided with the usual tip-forming cavity j , into which paste is conveyed from the paste-cylinder K through the tube k and orifice k' . The pasting devices form no part 50 of this present invention and will not therefore be particularly described. The stretcher is adjustably connected to the bracket J' by means of the set-screw j' , which passes through a slot in the bracket, and the bracket 55 is adjustably connected to the standard a^2 by means of a set-screw j^2 , which passes through a slot in the standard a^2 .

L is the wrapper-supporting table, which is 60 adjustably connected to the plate m by means of the screw-bolt m' , attached to the table L, which passes through the slot m^2 in the plate m and receives the clamping-nut m^3 . The plate m is provided at one corner with a post M, which is revolubly supported in suitable 65 bearings $n n$, as seen in Figs. 2 and 3. In order to rotate the post M, I provide a sleeve

O, fitting over the post M between the bearings $n n$. This sleeve is connected to the post by means of a pin o, which passes through the sleeve and a slot o' in the post, as seen in Fig. 70 6. By this arrangement the sleeve has a limited vertical movement relative to the post, but both have a uniform rotary movement. The sleeve is provided with upper and lower beveled gears $o^2 o^3$, which, however, have teeth 75 only on one-fourth of their circumference, in order to give the post and table only one-fourth of a complete revolution.

The shaft d is provided with a pinion p, meshing with the gear p' on the shaft p^2 , supported in suitable bearings, and the shaft p^2 carries a bevel-gear p^3 , with which the gears $o^2 o^3$ are adapted to be brought into engagement at the will of the operator. Q is a lever provided at one end with a strap q to engage 80 the sleeve O. This lever is pivoted on a standard q' , and a spring q^2 , attached to its other end and to the bed-plate A, normally tends to keep the gear o^3 in engagement with the gear p^3 , and preferably this engagement 85 between the gears o^3 and p^3 will turn the table one-quarter of a circle from the position it occupies in Fig. 1, in full lines to the left, as indicated by the dotted lines in said figure.

In order to bring the gear o^2 into engagement with the gear p^3 a rod q^3 is connected to the lever Q in front of its pivot and to a treadle beneath the bed-plate, (not shown,) which enables the operator at his pleasure to depress the front end of the lever against the 90 force of the spring q^2 , and so pull the sleeve O down and bring the gear o^2 into engagement with the gear p^3 . This will cause the table to move from the position indicated in dotted lines in Fig. 1 to that shown in full lines. In 95 order to give the table L vertical adjustment relative to the rollers C and D, a collar R is placed on the post M, which collar rests on the lower bearing n. A set-screw r passes through the collar R and engages the post M. 100 By loosening the screw r the post can be elevated or lowered, as desired.

I have herein particularly described and illustrated only two adjustable presser-rollers, but it is evident that four or even more 115 such rollers may be employed, as indicated in Fig. 7, as it would only require a duplication of the adjusting devices employed for the two rollers.

S is a finger for holding the tuck end of the 120 wrapper at the beginning of the wrapping operation. This, however, is not an essential feature of my invention, and will not therefore be particularly described.

The advantage of the pivoted table is that 125 it brings the wrapper into the necessary position to properly wind it spirally on the bunch without straining the wrapper, as is the case when the wrapper-table is moved lengthwise of the bunch.

130 The principal advantage of the adjustable presser-rollers is that it enables the operator

to apply substantially uniform pressure throughout the length of the bunch irrespective of its shape. Where a single straight roller has heretofore been used the pressure on bunches tapering toward both ends was necessarily only on a limited portion of the bunch, and, owing to inadequate pressure, the bunch was often thrown out of the machine by the operation of the positively-driven rollers. By my improvements the cigar-bunch is securely held in position with its tip end in the tip-forming cavity of the stretcher, and this is very important, as it is well known that the tip is the most difficult part to properly wrap.

Having described my invention, what I claim as new, and desire to secure by Letters Patent, is—

1. The combination with cigar-bunch supporting and rotating rollers, of a series of adjustable presser-rollers supported end to end, substantially as and for the purpose set forth.

2. The combination with cigar-bunch supporting and rotating rollers, of a series of presser-rollers supported end to end and separately adjustable to conform to the shape of the cigar-bunch, substantially as and for the purpose set forth.

3. The combination with cigar-bunch supporting and rotating rollers, of a series of spring-actuated presser-rollers supported end to end and separately adjustable to conform to the shape of the cigar-bunch, and means to lift the presser-rollers out of engagement with the cigar, substantially as and for the purpose set forth.

4. The combination with cigar-bunch supporting and rotating rollers, of a series of presser-rollers supported end to end and separately adjustable to conform to the shape of the cigar-bunch and also conjointly adjustable longitudinally relative to the supporting and rotating rollers, substantially as and for the purpose set forth.

5. The combination with cigar-bunch supporting and rotating rollers, of a series of presser-rollers supported end to end and separately adjustable to conform to the shape of the cigar-bunch, and also separately adjustable laterally relative to the supporting and rotating rollers, substantially as and for the purpose set forth.

6. The combination with cigar-bunch supporting and rotating rollers, of a series of presser-rollers supported end to end and separately adjustable to conform to the shape of the cigar-bunch, and also both separately and conjointly adjustable vertically relative to the supporting and rotating rollers, substantially as and for the purpose set forth.

7. The combination with cigar-bunch supporting and rotating rollers, of a post adjustable vertically and laterally of the said roll-

ers, a plate carried by the post, a second plate hinged to the first plate, a spring normally tending to force the plates together, a series of presser-rollers carried by said second plate, and means to separate said plates against the force of the spring, substantially as and for the purpose set forth.

8. The combination with bunch supporting and rotating rollers, of a plate supported on the frame of the machine, a second plate having a hinge connection with the first plate, boxes on said second plate, rods journaled in said boxes and capable of having longitudinal and rotary movement therein, means to lock the said rods in the boxes in the desired position, and presser-rolls carried by said rods, substantially as and for the purpose set forth.

9. In a cigar-machine, the combination with bunch supporting and rotating rollers, of a plate supported on the frame of the machine, a second plate having a spring-hinge connection to the first plate, rods supported in said second plate and capable of having rotary and longitudinal movement therein, presser-rollers carried by said rods, and a device to adjust the two plates relative to each other against the force of the spring-hinge, substantially as and for the purpose set forth.

10. In a cigar-machine, the combination with cigar-bunch supporting and rotating rollers, of presser-rollers, a wrapper-stretcher, a pivoted wrapper-supporting table, and mechanism to move the table on its pivot toward and away from the said stretcher, substantially as and for the purpose set forth.

11. In a cigar-machine, the combination with cigar-bunch supporting and rotating rollers, of presser-rollers, a wrapper-stretcher, a wrapper-supporting table, a post to which said table is adjustably secured, bearings in which said post rotates, a sleeve on the post connected therewith to have independent vertical movement and uniform rotary movement, upper and lower bevel-gears on said sleeve, a positively-driven bevel-gear supported adjacent to the sleeve, and suitable devices to bring the bevel-gears on the sleeve into engagement with the positively-driven bevel-gear, substantially as and for the purpose set forth.

12. In a cigar-machine, the combination with cigar-bunch supporting and rotating rollers, of presser-rollers, a wrapper-stretcher, a pivoted wrapper-supporting table, and means to adjust said table vertically and horizontally relative to the supporting and rotating rollers, substantially as and for the purpose set forth.

In testimony whereof I affix my signature in presence of two witnesses.

JOHN BUNN.
